The ornamental design for a fuse, as shown and described.

DESCRIPTION1. **Fuse**

1.1 : Perspective

1.2 : Front

1.3 : Back

1.4 : Top

1.5 : Bottom

1.6 : Right

1.7 : Cross-sectional

1.8 : Cross-sectional

The fine lines on the surface of the article depict three-dimensional shape of the surface; the diagonal surface shading lines indicate that a plate part provided at the front side is transparent; FIG. 1.7 is a cross-sectional view cut vertically at the center of the front view; FIG. 1.8 is a cross-sectional view cut horizontally at the center of the top view; the left view is omitted since it is symmetrical to the right view.
